UNITED STATES PATENT OFFICE.

HERMAN FREGIN, OF CHICAGO, ILLINOIS, ASSIGNOR TO D. M. O'NEIL, OF CHICAGO, ILLINOIS.

AIR-WASHING AND VENTILATING MACHINE.

Application filed March 3, 1919. Serial No. 280,224.

To all whom it may concern:

Be it known that I, HERMAN FREGIN, a citizen of the United States of America, and a resident of Chicago, county of Cook, and State of Illinois, have invented certain new and useful Improvements in Air-Washing and Ventilating Machines, of which the following is a specification.

This invention relates to means of compact form adapted for supplying and circulating fresh air, regulating the temperature and humidity thereof and purifying the same, and particularly to self-contained, unitary devices of the character stated, adapted for use in living rooms, schools, offices, restaurants, public halls and the like, especially where no adequate means for supplying the needs are incorporated in the design of the building.

It has long been known that excessive and continued dryness of the air is likely to cause low personal efficiency, discomfort, sore throat, colds and general illness, particularly in the winter time, when rooms are frequently overheated and the air is usually too dry, and therefore most likely to contain dust and germs. Moreover, unwashed air in cities carries more or less fine soot which ordinary ventilating apparatuses and screens fail to remove.

The main objects of this invention are to provide an improved form of combined air-washing, attemperating, ventilating and humidifying means; to provide such a device adapted to warm the air in winter and to cool it in summer; to provide and assemble such a device efficiently in a common housing; to provide for ready portability of such a device; to provide apparatus therefor adapted for simple operation and control; to provide such a device suitable for construction in either small or large units as may be desired, and adapted for use either in dwelling houses, office buildings, factories, or other places wherever desired; to provide for interchangeability of parts; and to provide an improved form of housing and arrangement of parts therein.

An illustrative embodiment of this invention and modifications of certain details are shown in the accompanying drawings, in which—

Fig. 1 is a perspective view of a device embodying the invention.

Fig. 2 is a section on the line 2—2 of 55 Fig. 4.

Fig. 3 is a section on the line 3—3 of Figs. 2 and 4.

Fig. 4 is a section on the line 4—4 of Fig. 2.

Fig. 5 is a section substantially similar to Fig. 3 but shows a plain paddle wheel blower and a group of impact spray generators.

Fig. 6 shows an end view of the impact spray generator assembly.

Fig. 7 is a conventional diagram of a preferred form of the device.

Fig. 8 is a face plan of a spiral discharge nozzle.

Fig. 9 is a section on the line 9—9 of 70 Fig. 10.

Fig. 10 is a section on the line 10—10 of Figs. 8 and 9.

Fig. 11 is a perspective view of the spiral core of the nozzle of Figs. 9 and 10.

Fig. 12 is a view of a nozzle.

Fig. 13 is a view of a spray making deflector.

Fig. 14 is a view of a remote control device.

Fig. 15 is a view of the air inlet for draining the nozzles.

Figure 16 is an axial section of the deflector of Figure 13.

In the construction shown in the drawings, the device as a whole comprises in combination mainly a rigidly framed housing or cabinet 1, an induction flue 2 for bringing in air from outside of the building, a fan 3 for propelling the air through said device and expelling same with sufficient force to cause circulation for a considerable distance into or throughout the room, a motor 4 for the fan, a heater 5 for warming the air, and means 6 for washing and supplying moisture to the air in the form of spray.

The cabinet 1 is of light and portable character, and in general external appearance somewhat resembles a high-grade cabinet style of phonograph, though it is preferably made of sheet metal and castings instead of wood and is given an enamel finish of any style desired. Said cabinet has a partition 7 arranged to provide substantially or in effect a U-shaped air path or flue, the arms of which lead upward to the top of the cabinet, the spraying means 6 being positioned in one arm near the bottom, the fan

3 in the other arm, and the warming means substantially in the bottom part of the flue and extending also up into the fan arm.

The air washing and moistening spray is 5 preferably applied to the air before it passes to the heater, and for this reason, the device is arranged with the air-supplying flue 2 connected to the arm 8 containing the spray producing means, and the fan 3 is located in 10 the arm 9 which discharges the heated air into the room. The flue proper, and particularly the induction arm 8, is to advantage made of sheet metal jointed tightly and arranged with a dead air space between the 15 walls thereof and the walls of the cabinet. The partition 7 causes the heated air to pass directly from the heater to the fan and prevents its being cooled by the flue 8.

The fan or blower 3 may be of any de- 20 sired type, provided that its capacity is sufficient to supply the required volume of air per minute and to create the necessary draft speed and momentum to effect circulation throughout the room, a paddle-wheel type 25 of rotary blower being preferable to a propeller type of fan for this purpose.

The motor 4 is preferably of a type adapted to be driven by electricity, though a water-driven motor or other means might 30 obviously be used, depending on the source of power available. Direct connection is provided for the motor and fan, as by shaft 10.

The heater 5 may be of any type consist- 35 ent with the source of heat, a steam radiator as here shown being preferable whenever steam is available. The heater is to advantage positioned at the foot of the discharge flue 9, so as to obtain the advantage 40 of some natural draft tendency, as will be understood.

The spraying means 6 are constructed and arranged to effect economically a most thorough washing of the air, and for this 45 purpose a very fine and evenly distributed spray is necessary. The spraying part may to advantage be made in the form of one or more pairs of nozzles (see Figs. 3 and 10) disposed with each pair coaxially facing 50 each other, and the pairs are arranged lengthwise of the vertical draft arm 8 in which they are disposed, there being preferably two pairs side by side. Each nozzle 6 is so constructed as to impart a spiral-like whirling motion to the water as it approaches and leaves the orifice, whereby 55 effective distribution of the spray throughout the full width of the flue is effected. By reason of the arrangement shown, the spray is delivered in the form of two cones, each extending at its base entirely across 60 the flue 8, so that the air all has to pass through a plurality of sheets of spray. These spray sheets may intersect as shown. 65 The bottom of the passage constituting

the bent U-portion of the flue is in part trough-like in character as at 11 and is provided with a drain-pipe 12 to carry off surplus moisture resulting from condensation and settling of the spray and unevaporated water particles. In order to effect separation of surplus moisture from the air, baffle means are provided in the form of plates 13, 14 and 15 between the spray chamber 70 and the radiator 5. Moisture from plate 15 is drained off by pipe 12'. The upward passageway between the walls 13 and 14 is provided with downwardly inclined drip baffles 13' and 14' to further eliminate surplus moisture. 80

In order to facilitate interchangeability of spray nozzles and associated parts, the flue containing same is made in sections having telescopic relation to one another, and the cabinet adjacent thereto is provided with a door or removable panel 16 whereby the nozzle-containing section may be removed whenever desired, either for repairs or for cleaning. 85

The cabinet 1 as a whole comprises mainly 90 a frame 17 including four upright corner members in the form of angular bars 18. These corner bars are fixed permanently at their ends to the rigid base 19 and to the top or cap member 20. The four upright 95 walls of the cabinet are in the form of sheet metal plates 21, 22, 23 and 24 secured at their edges to corner bars 18, as by means of screws 25 which are concealed by means of removable finishing corner beads 26. 100 Whenever necessary these wall plates may be removed.

For convenience in describing the device more specifically the side 21 adjacent to which the air intake flue 2 is positioned is 105 designated the "back," the opposite side 22 the "front" and as viewed from the front of the device, the other two sides 23 and 24 are designated "left side" and "right side" respectively. 110

The discharge arm 9 of the draft flue is somewhat larger than the intake side 8 and includes a sharp reverse bend just below and adjacent to the fan. A horizontal seat 28 is provided in the space 29 in front of the upper part of the flue arm 9 on which shelf the direct-connected motor and fan are mounted, a block of cork 28' or other jar-absorbing material being interposed for the motor to bear upon. 115

The fan or blower 3 is of the paddle-wheel type, and comprises a hub 30 fixed on the shaft 10, and a plurality of similar arms 31 radiating therefrom at each side, each arm on one side of the hub being positioned opposite a corresponding arm on the other side. Each pair of arms having the same angular position is provided in the form shown in Fig. 3 with a pair of plates or blades 32 and 33 disposed on opposite sides near their 120

outer extremities, one plate 32 being positioned outward radially somewhat farther than the other. Said plates are curved as shown in Fig. 3, and cooperate to impart an outward thrust to the air which is drawn in centrally of the fan casing at the eye 35 on the side opposite from the motor, the motor side being entirely closed by a plate or wall 37. A fan casing extends upward and constitutes part of the discharge end of the flue, said casing including a curved plate 38 and a pair of similar flat plates 39 secured by bolts 40. This casing is also provided with a guide wall 38' extending in a generally diagonal direction downward across the top of the fan oppositely of the direction of rotation and terminates at a point approximately over the center of the fan where said wall is about horizontal, as shown in Fig. 3.

Referring to Fig. 5, the form here shown is mainly similar to Fig. 3, but the blower and spray generators are of somewhat simpler construction. The fan 3' is provided with a single plain blade or paddle 41 for each pair of arms.

The spray generator of this figure comprises a liquid supply tube 45 disposed horizontally, in combination with a rod 46 disposed parallelly thereto in spaced relation underneath, said tube having discharge apertures and nozzles 47 directed toward said rod and the latter having upwardly facing dished deflectors 48 arranged in alignment with the nozzles 47 respectively, so as to dash the several streams into spray sheets by means of the liquid impact, the several sheets being substantially in the form of conical jets, which more or less overlap one another.

The tube 45 is supported by a pair of lugs 50 and the rod 46 is secured to the tube 45 by means of uprights 51 also in the form of rods. Each nozzle 47 is screwed into the tube 45 and is designed to produce a small solid stream. Each saucer-like plate 48 is mounted on a small post 52 screwed into the rod 46. The impact of the stream perpendicularly against the plate disperses the water as a sheet of spray.

Referring to the embodiment of Fig. 3 and the details of Figs. 8 to 11, each of the nozzles 6 comprises a central body part 55 of thick disk shape, having an axial threaded projection 56 on one side and the other side being shouldered peripherally and provided with a removable threaded cap 58. Said cap has a concave outer face and is provided with a central discharge aperture 60 for the jet. A spiral chamber 61 is provided between the body part and the cap, and an intake passageway 62 extends axially through said threaded projection to the outer part of the spiral chamber. The depth of the chamber diminishes from the

outer part inward toward the center where adjacent to the jet aperture it is very shallow. By this construction the cross section of the spiral part diminishes toward the center and the speed of the water is greatly accelerated, and as will be seen by reference to Fig. 11, the floor 63 of the passageway ascends gradually from the outer part toward the center.

The discharge end of the fan flue 9 is provided with an enlargement 65 at or near the top, which serves somewhat in the capacity of a muffler to reduce or suppress any sound caused by the fan. The top piece 20' rests demountably on the frame part 20. It has a central opening 20" fitted with a grid 67.

The motor is provided with a manual control device 70 which may be mounted either in the front part of the cabinet as in Fig. 2 or may be placed at a distance and connected with the motor by means of a cable, as will be understood, so that the starting and stopping of the device, as well as the operating speed, may be controlled if desired by a person in a remote part of the room, as for instance, at a desk where the switching means may be mounted.

In order to efficiently operate such a device as herein set forth under normal all-the-year-around conditions, it is necessary to control the supply of heat independently of the rest of the apparatus, for at times as in hot weather the device must be capable of running without any addition of heat. The air intake closure 73' and water supply valve may to advantage be controlled by a common handle 73 (see Fig. 7), because all air used is to be washed, and when the spray is stopped the air should be cut off also. It is sufficient if the movement be limited to "off" and full "on" positions. In order that the fan motor may be controlled from a distance, it is in some instances advantageous to provide an independent starter therefor, and such controller may to advantage be adapted for a plurality of motor speeds so that the draft strength may be readily controlled by the user according to the state of the weather. All of the several control means may, of course, be connected for common coaction if desired, but such an arrangement need not be described as it is not generally advantageous and is not claimed as a part of my invention.

The device as a whole may be made more or less portable in form by mounting on casters 75 (see Fig. 5) and supplying flexible tubing for the air, water and steam connections as will be understood though not fully shown in the drawings.

In hot weather the steam, of course, need not be connected. The temperature of the air is fortunately much reduced by the spray and by the evaporation of a consider-

able amount of water. A still further lowering of temperature may be obtained if desired by introducing ice into the radiator chamber, to accommodate which the radiator 5 may be removed during the summer, or a refrigerating coil 76 may be used.

In winter the air may to advantage be warmed somewhat before as well as after passing through the spray, in order that it 10 may take up enough moisture to insure against the excessive dryness that usually prevails in the air of heated rooms in cold, dry seasons. For this purpose a few coils of steam pipe may be provided in the flue 15 arm 8 as at 78 (see Fig. 7). The ammonia coil 76 may if preferred be disposed to cool the air before washing, for which purpose it may be mounted in the passageway 8 above the spray nozzles, as will be understood.

The water supply is controlled by the main valve 80 in the main 81. An air cock 82 permits letting air into the nozzles when the water is shut off, so as to avoid danger 25 of freezing in cold weather.

The air-treating device as a whole is well adapted for use in connection with a system of telephone booths or other enclosed compartments; as for example, in a phonograph 30 store where a number of demonstration booths (not shown) may be connected by a branched tubular connection 85 to the discharge opening of the air-treating machine herein-described, as illustrated diagrammatically in Fig. 7.

The spray chamber is in the form of a tank-like receptacle 87 in which is set the baffle plate 13 and also the spray means. Said receptacle 87 has a removable cover member 88 extending to but not covering the passage between walls 13 and 14. The cover 35 88 has an upward intake projection 88'. The air supply flue 8 leading downward from the induction flue 2 to the cover neck 88' includes a pair of telescopically joined sections 89 and 90, the latter also having similar connection to said part 88', the joints 91, 92 and 93 being substantially alike.

The horizontal wall 95 serves to divide 40 the cabinet space as a whole nearly equally, the upper space being somewhat the greater. The flue 8 extends through said wall 95 near one side and an air passage aperture 96 is provided over the radiator at the other 45 side.

The fan wall plates 39 and the shelf 28 extend entirely across the cabinet from the right side to left side, so that the motor compartment 29 having door 29' is separate 50 from the rest of the interior. Said plates 39 are in the form of castings and are provided each with a guide rib 97 against the inner side of which is disposed the curved sheet metal fan-wall 38. A series of small knobs or lugs 98 are disposed just inside the

wall 38 to hold the latter snug and air-tight against said rib. This prevents leakage of air and makes for fan efficiency.

The radiator 5 is provided with inlet and outlet pipes 101 and 102 respectively and also 70 has an air valve 103. An inlet aperture 105 is provided in the left wall 23, near the top, for admitting the necessary power leads for the motor, as will be understood.

Although the device may be to a considerable degree portable, still it is ordinarily more or less permanent in character when once installed, much as a stove may be so regarded. In order that it may be positively fixed to the floor whenever desired, the 80 flange 19' of the base is provided with holes 19" adapted to receive screws or the like.

The top frame part 20' and grid 67 may well be cast integrally if desired.

The air cock 82 may be of a simple type 85 adapted for operation by hand, but in order that the nozzles may be drained automatically and without burdening the mind of the attendant, a gravity-operated form of valve is provided, including a ball 107 90 arranged to be forced by the water up against the seat 108 to close the valve port 109 and to be released from the seat by gravity as soon as the water pressure is released, as by closing valve 80.

The variable speed device 110 of Fig. 14 is a combined switch and rheostat of a form adapted for desk use, when remote control is desired. Said device 110 has the necessary terminals 111, a pair of push buttons 112 and a contact arm 114 controlled thereby so as to play over a series of resistance contacts 115 so as to cut in and out resistance whenever it is desired to alter the speed of the motor.

Although but two embodiments of this invention are herein shown and described, it is to be understood that numerous details of the constructions shown may be altered or omitted without departing from the spirit of the invention as defined by the following claims, and that the features of primary importance are common to both forms.

I claim:

1. An air washing and moistening device, comprising in combination an air passageway, means for propelling air therethrough, closure means for said passageway, means for spraying the air in said passageway to wash and moisten the same, means for controlling the supply of water to the spraying device, and a manually operable member connected to both said closure means and said last-mentioned means, whereby their control is coordinated and their respective opening and closing rendered simultaneous.

2. In an air washing and moistening device of the character described, a cabinet having a draft flue comprising

ing, in combination, a plurality of telescopic sections, one of which is separable from the others, and means mounted in one of said sections adjacent to said removable section for supplying a spray of water to the air passing through said flue, and said cabinet having means of access opposite said one section whereby the latter may be removed for access to said spray supplying

means.

3. An air washing and ventilating machine of portable self-contained and unitary character, comprising in combination a com-

pact upright housing cabinet provided with a U-shaped flue, the discharge arm of which extends to the top of the cabinet, an induction flue communicating with the other arm of said flue for supplying out-door air, and means in the first mentioned flue for propelling the air through said device, and spray means in said other arm for thoroughly washing the air.

Signed at Chicago this 21st day of February, 1919.

HERMAN FREGIN.
